UNITED STATES PATENT OFFICE

2,050,765

TOBACCO STEMMING MACHINE

Rupert E. Rundell, Rockville Centre, N. Y., assignor, by mesne assignments, to American Machine & Foundry Company, a corporation of New Jersey

Application April 19, 1933, Serial No. 666,896
Renewed April 10, 1935

20 Claims. (Cl. 131—57)

This invention relates to tobacco shredding machines for the purpose of shredding tobacco and separating the leaf fragments and stem portions from each other. The principal objects of the present device are to provide a simpler and more compact device for this purpose which is nevertheless equal to or greater in efficiency as well as capacity than larger existing types of machines, and to provide a machine which utilizes centrifugal force to feed the tobacco leaves and portions thereof through the shredder.

Other objects are to provide a tobacco shredder with shredding pins which are to an extent self feeding, that is help the progress of the leaves in the desired direction of feed; to provide for winnowing by fan means in the same unit and in some forms on the same shaft as the travelling member of the shredder; to provide a shredder the shredding elements of which are to a large extent self cleaning; and to provide for feeding leaf blade portions rapidly through the shredding mechanism after their separation from the tobacco stem to thereby make possible large leaf shreds and at the same time to retain the stems a somewhat longer time if necessary to provide for thorough cleaning of blade portions therefrom.

Another object of the invention is to provide a compact unit which may be combined with other tobacco leaf treating machines to supplement the main treating operation with little or no manual re-handling of the leaves and without loss of condition on the way. With these and other objects not specifically mentioned in view, the invention consists in certain constructions and combinations which will be hereinafter fully described and then particularly pointed out in the claims hereunto appended.

In the accompanying drawings, in which like characters of reference indicate the same or like parts, Fig. 1 is a sectional side elevation partly broken away of the improved leaf shredding machine; Fig. 2 is a sectional front elevation of the same; Fig. 3 is a sectional side elevation partly broken away of a duplex leaf shredding machine; Fig. 4 is a plan view of the duplex machine shown in Fig. 3; Fig. 5 is a side elevation showing the use of the improved shredding machine in combination with a tobacco stemming machine; and Fig. 6 is a cross section on line 6—6 of Fig. 5 showing the arrangement of the thresher unit of the stemming machine.

In carrying the invention into effect there is provided in combination with a rotary conical

tobacco breaker or shredder having a peripheral outlet, means for guiding tobacco to be broken to a position adjacent the apex of the cone to be urged through the breaker by centrifugal force. In the best constructions said breaker includes relatively movable members and a winnowing fan traveling with one of said movable members. Preferably said relatively moving members are provided with sets of breaking elements on each of said members, said elements being arranged with the elements on one passing between the elements on the other, and in one preferred construction said elements have inclined faces the planes of which are inclined toward the base of the cone from the leading to the trailing edges of said faces to fan leaf portions through the breaker or shredder. In one preferred application of the invention there is provided in combination with a tobacco stemming machine having butting means, a shredding unit and means co-acting with said butting means to deliver leaf portions and broken butts from said butter into the range of action of said shredding unit whereby the tobacco portions removed by the butter may be reclaimed without rehandling or reconditioning.

Referring to Figs. 1 and 2, the main frame of the machine consists of frame elements 7 and 8, which are held together by tie bolts 9 and which carry in bearings 10 and 11 a shaft 12 driven by a pulley 13. On bearing 11 is mounted a stationary hub 14 which carries a conical shell 15 provided with internally projecting pins 16 fastened to radial external reinforcing strips 17. At the top of shell 15, two of the strips 17 are omitted to leave room for an opening 18 communicating with a chute 19 through which the leaves L are fed into the machine. The chute 19 is supported by straps 20 and 21 attached to the frames 7 and 8, respectively.

On shaft 12 is rotatably mounted a hub 22 supporting the rotatable cone shell 23 having externally projecting pins 24 attached to internal reinforcing strips 25. While the stationary pins 16 are preferably square, the revolving pins 24 are in one preferred embodiment of the invention are rectangular and are set with their long sides at a forward angle with the direction of rotation so as to drive the leaf fragments severed by them towards the large ends of the cones, and so be self clearing in that the tendency of the stems will be to slide off the forward surface of the pins rather than hang thereon as might be the case with a radial surface. To provide an outlet the stationary cone 15 has a cylindrical

outward extension 26 with an outlet opening at its forward side, in the direction of rotation. Into this extension is inserted an annular plate 27 partly cut away so as to cover nearly all the 5 annular space between the cones 15 and 23 not registering with the outlet opening of cylinder 26. The plate 27 is reinforced by an eccentric rib 28 which at its innermost end is turned radially outward, thereby closing up the outer annular 10 space of extension 26 at the upper end of its outlet. At its forward end, the extension 26 is closed by a disk 29 having a central opening for the admission of air.

Within the extension 26, there is mounted on 15 the same shaft 12 carrying the rotating cone or shell 23, a fan 30 having radial vanes 31 attached to a solid rear disk 32 carried by a hub 33. The front of the fan is closed by a disk 30 having a central opening corresponding with 20 that in disk 29. The air inlet is controlled by a disk valve 36, shown in Fig. 3, which is pivoted on frame 7 and adapted to cover up more or less of the opening in disk 29, as required. At its outer end, the extension 26 is reinforced by 25 an angle frame 34 by which it is fastened to frame 7 through a cross strap 35 at the bottom center, and through spacers 36 along the top half.

To separate stem portions from leaf portions 30 the outlet of extension 26 through a pipe 37 communicates with a chamber 38 which is divided into three sections by means of vertical partitions 39 and 40 extending nearly to the closed top of the chamber, which is open at the 35 bottom. The space between the top of partition 40 and the top of chamber 38 is bridged by a screen 41 attached to partition 40. In the first section of the chamber, opposite the entrance of pipe 37, is mounted an adjustable baffle plate 42 which directs the fragments forced into pipe 37 by fan 30 in an upward direction. The stem fragments S, being heavier than the leaf fragments, are not carried to the top of partition 39 but drop from the first section of chamber 38. The leaf fragments L, on the other hand, are 45 blown over the top of partition 39 into the second section of chamber 38 in which they fall to the bottom outlet. The leaf fragments are prevented from entering the third section of chamber 38 by the screen 41, but the dust particles 50 D liberated from the leaves and the tobacco dust produced by the shredding operation will pass through the screen and issues from the outlet of the third chamber section.

In Figs. 3 and 4, a duplex leaf shredder based 55 on the cone principle is shown. Two shredder cone units as heretofore described are mounted, with the cone hubs facing one another, on a common shaft 43, supported by frames 44 and 45 and driven by a pulley or sprocket 46 mounted 60 at its center, between the two cone units. The pulley 46 is connected by a belt with a pulley 47 on a countershaft 48 journaled in frames 44 and 45 and driven by a pulley 49 belted to a motor 50. The shaft 48, by pulleys 51 and 52, 65 drives a shaft 53, which in turn, by pulleys 54 and 55, drives a shaft 56 on which is mounted a roller 57 driving an endless belt 58 running over rollers 59 on shaft 60 supported by a pedestal frame 61.

The belt 58 runs towards the cone units and 70 serves as a feed conveyor for the leaves L to be shredded. It occupies the entire width between the discharge chambers 62 and its upper loop is supported by a plate 63 held by brackets 64

mounted on shafts 56 and 60. The leaves are placed on feed belt 58 between end guards 65 which lead to the outside walls of the entry chutes 66 of the shredding units. Over the center of belt 58 there is suspended a forked 5 guide 67 the ends of which form continuations of the inside walls of the chutes 66. At the bottom of the outlet openings of the outer core extensions 26 are placed screens 68 permitting the dust D to fall through a chute 69 into a 10 receptacle 70. Long stems S slide down baffles 71 placed atop the first partitions 72 of chambers 62 into receptacles 73, short stems S' are carried to plates 74 atop the second partitions 75 and drop into receptacles 76, while leaf fragments L are blown beyond the plates 74 and land in receptacles 77.

In Fig. 5, the improved shredding machine is illustrated combined with and supplemental to a tobacco stemming machine of the type disclosed 20 in my prior Patent No. 1,968,098 granted July 31, 1934, though it will be understood that the present shredder or breaker is applicable to a wide variety of stemmers and other tobacco machines. In this particular stemming machine, 25 the leaves L fed on an endless belt A are first subjected to a threshing mechanism B to clear the butt ends of the stems, are then separated by pairs of belts C running at progressively increasing speeds, and are delivered by a belt 30 runway D to a leaf carrier chain G which grips the stem butts and carries the leaves through the stripping mechanism H, the severed tobacco T dropping into a receptacle E while the stems S are removed from the grippers by ejecting 35 roller J and guided by a chute K into a receptacle F.

The threshing mechanism B, Fig. 6, consists of two oppositely revolving shafts 78 upon which are mounted blocks 79 carrying brackets 80 in which are pivoted rows of beaters 81. The leaves L are guided through the threshing mechanism by the feed belt A and the endless thresher belt B, and the violent action of the beaters 81, instead of merely clearing the butts, breaks off 45 many of them still uncleared with good tobacco adhering which hitherto could not be economically reclaimed. It is for the purpose of taking the tobacco off these uncleared stem butts, and also for separating the tobacco particles from 50 the stem fragments that it is desirable to use the improved shredding machine in conjunction with the tobacco stemmer. It should be observed that all manual rehandling is eliminated and that the tobacco, which dries and loses its carefully 55 prepared condition or moisture content for stemming is shredded before it loses condition and therefore no reconditioning operation is necessary.

In Fig. 5, the shredder 7 is placed with its intake chute 19 below the outlet of the threshing mechanism B so that the fragments M drop directly into the space between the cones 15 and 23. After being shredded by the said cones, 60 the fan 30 blows them into chamber 38, from 65 which the heavier stem portions fall through the lower outlet 82 upon an endless belt 83 which carries them to a container 84 communicating with the stem receptacle F of the stemming machine, while the lighter tobacco fragments are blown to the top of chamber 38 and drop through the upper outlet 85 into a container 86 communicating with the tobacco receptacle E of the stemming machine.

It will be seen that the compactness of the 75

present device is such that it may advantageously form a part of a variety of tobacco machines for salvaging tobacco adhering to or mixed with the stems.

- 5 In the operation of the improved tobacco shredder the tobacco after being fed in between the conical faces of the members 15 and 23 is urged through the shredding elements 16 and 24 by centrifugal force, as well as gravity, which
- 10 speeds up the shredding process and increases the capacity of the machine. It is also noted that the pins or breakers or shredding elements are made of flat stock having their flat faces inclined to the direction of their movement, the
- 15 inclination of the plane of the shredding elements being toward the outlet edge of the cone from the leading to traveling edge of the elements, whereby the surface facing the base of the cone will fan the leaves toward the outlet
- 20 at said cone base. The inclined faces of the pins will also produce a current of air along the surface of the cone 25 towards said outlet which in addition to the similar effect of the fan 31 will draw the separated leaf portions rapidly
- 25 through the shredding elements. This tends to blow out the larger leaf portions immediately after they are separated from the stems and makes for larger shreds which is a desirable feature since these shreds make a better grade
- 30 of filler for cigars. This same air current will have relatively less effect on the stems which will remain in the shredding portion of the machine until the leaf portions are removed.

The mounting of the fan on the same shaft as the one of the conical shredder members at the periphery makes for compactness and simplicity and also has a tendency to draw air from inlet to periphery of the conical surfaces and to augment the air current produced by the inclined

40 breaker element surfaces.

What is claimed is:

1. In a tobacco stemming machine, the combination with tobacco shredding members one of which rotates relative to another, having opposed conical faces and coating shredding elements in each of said faces arranged to shred tobacco leaves, and means for feeding tobacco leaves between said faces near the apex thereof for movement during shredding toward the base
- 45 of the conical faces the shredding elements on said relatively rotating member having flat faces inclined to the direction of their movement from a position nearest said apex at the leading edge of the face to a position nearest said base at
- 50 the trailing edge of said face, to fan the tobacco portions toward said base.

2. In a tobacco stemming machine, the combination with tobacco shredding members one of which rotates relative to another, having opposed conical faces and coating shredding elements in each of said faces arranged to shred tobacco leaves, and means for feeding tobacco leaves between said faces near the apices thereof for movement during shredding toward the

65 base of the conical faces, said elements having their leading faces inclined rearwardly from base to tip to prevent hanging of tobacco portions thereon.

3. In a tobacco shredder, the combination with opposed relatively movable members, of tobacco shredding elements on said members the shredding elements on at least one of said members comprising combined shredding pins and fans, whereby a current of air is produced

75 by said fans between said members which tends

to blow out the larger leaf portions immediately after they are separated from the stems.

4. A multiplex tobacco shredder comprising in combination a plurality of tobacco shredders arranged for rotation on a common horizontal axis, common means for feeding tobacco toward said shredders, and means for diverting a part of the tobacco on said feeding means to each of said shredders.

5. A multiplex tobacco shredder comprising in combination a plurality of tobacco shredders arranged for rotation on a common horizontal axis, common means for feeding tobacco toward said shredders, and means for diverting a part of the tobacco on said feeding means to each of said shredders, and winnowing devices arranged to receive tobacco from said shredders, flanking said feeding means.

6. In a tobacco shredder, the combination with opposed relatively movable tobacco shredding members arranged to shred tobacco introduced between them, and means disposed between said members for producing a current of air between said shredding members in a direction at an angle to the direction of movement of the members.

7. The combination with a rotary conical tobacco breaker having one tangential outlet, of means for guiding tobacco to be broken to a position adjacent the apex of the cone, a revolute fan in said breaker adjacent said outlet, and an air inlet adjacent said fan, whereby rotation of the fan produces a blast of air which forces all of the broken tobacco through said outlet.

8. The combination with a rotary conical tobacco breaker having a tangential outlet, of means for guiding tobacco to be broken to a position adjacent the apex of the cone, a chamber communicating with said outlet and having three sections, said breaker including relatively movable members and a winnowing fan travelling with one of said movable members and blowing the stem fragments, leaf fragments and dust through said outlet into the first, second and third sections respectively of the chamber.

9. The combination with a rotary conical tobacco breaker having a tangential outlet, of means for guiding tobacco to be broken to a position adjacent the apex of the cone, said breaker including relatively movable members and set of breaking elements on each of said members arranged with the breaking elements on one member passing between the breaking elements on the other member, the breaking elements on one member being rectangular and set with their long faces at a forward angle to their direction of rotation to drive the broken leaf fragments toward the base of the cone.

10. The combination with a rotary conical tobacco breaker having a tangential outlet, of means for guiding tobacco to be broken to a position adjacent the apex of the cone, said breaker including breaker pins having fan surfaces facing the outlet of the breaker for fanning the leaf fragments broken from the tobacco towards said outlet, whereby said fan surfaces will produce a current of air through the breaker which will tend to blow out the larger leaf portions immediately after they are separated from the stems.

11. In a tobacco stemming machine, the combination with tobacco shredding members one of which rotates relative to another, having op-

- posed conical faces and coacting shredding elements in each of said faces arranged to shred tobacco leaves, means for feeding tobacco leaves between said faces near the apices thereof for movement during shredding toward the base of the conical faces, and mechanism for removing the shredded tobacco from between said conical faces and winnowing it into stem fragments, leaf fragments, and dust.
10. 12. In a tobacco stemming machine, the combination with tobacco shredding members one of which rotates relative to another, having opposed conical faces and coacting shredding elements in each of said faces arranged to shred tobacco leaves, means for feeding tobacco leaves between said faces near the apices thereof for movement during shredding toward the base of the conical faces, a winnowing fan at the base of said conical faces for winnowing the shredded tobacco, and an arcuate annular plate covering only the upper half of the annular space between the base of said conical faces, whereby the broken tobacco is withdrawn through the bottom of said annular space by said fan.
15. 13. In a tobacco stemming machine, the combination with tobacco shredding members one of which rotates relative to another, having opposed conical faces and coacting shredding elements in each of said faces arranged to shred tobacco leaves, means for feeding tobacco leaves between said faces near the apices thereof for movement during shredding toward the base of the conical faces, a shaft carrying and driving one of said members, a winnowing fan carried by said shaft, and a cylindrical extension enclosing the fan and the base of said conical faces and provided with an outlet for the broken tobacco and an air inlet adjacent said fan.
20. 14. The combination with a rotary tobacco shredder having opposed surfaces of progressively increasing circular cross-section and a tangential outlet, said surfaces being provided with tobacco breaking elements, of means for feeding tobacco between said surfaces at one end thereof for movement under the influence of centrifugal force to said tangential outlet, a revoluble fan adjacent said outlet, and an air inlet adjacent said fan, whereby rotation of said fan produces a blast of air which forces all the broken tobacco through said outlet.
25. 15. The combination with a rotary tobacco shredder having opposed surfaces of progressively increasing circular cross-section and a tangential outlet, said surfaces being provided with breaking elements, of means for feeding tobacco between said surfaces at one end thereof for movement under the influence of centrifugal force to said tangential outlet, and a rotating winnowing fan travelling in unison with one of said surfaces positioned to blow the broken tobacco through said outlet and winnow it into stem fragments, leaf fragments, and dust.
30. 16. The combination with a conical tobacco shredder having a tangential outlet and an apical inlet, of means for feeding tobacco to be shredded into said inlet, and means for forcing the shredded tobacco through said outlet and winnowing it into stem fragments, leaf fragments, and dust.
35. 17. The combination with a butt thresher, of mechanism for stripping tobacco from the stems
- of tobacco leaves, means for forwarding tobacco leaves into the range of action of said thresher and stripping mechanism successively, a shredder arranged to receive leaf fragments and broken butts from said thresher and shred the same and thus remove any leaf fragments adhering to the broken butts, and a winnowing fan for removing the shredded tobacco from said shredder and separating the shredded leaf fragments from the shredded butts and delivering the shredded leaf fragments to tobacco stripped from the leaves by said mechanism.
40. 18. The combination with a butt thresher, of mechanism for stripping tobacco from the stems of tobacco leaves, means for forwarding tobacco leaves into the range of action of said thresher and stripping mechanism successively, a shredder arranged to receive leaf fragments and broken butts from said thresher and shred the same and thus remove any leaf fragments adhering to the broken butts, and a winnowing fan for removing the shredded tobacco from said shredder and separating the shredded leaf fragments from the shredded butts and delivering the shredded leaf fragments to tobacco stripped from the leaves by said mechanism, said shredder including relatively movable tobacco shredding members arranged to receive leaf fragments and broken butts therebetween from said thresher and shred the same, and fan means on one of said members for feeding the tobacco through the shredder.
45. 19. The combination with a butt thresher, of mechanism for stripping tobacco from the stems of tobacco leaves, means for forwarding tobacco leaves into the range of action of said thresher and stripping mechanism successively, a shredder arranged to receive leaf fragments and broken butts from said thresher and shred the same and thus remove any leaf fragments adhering to the broken butts, and a winnowing fan for removing the shredded tobacco from said shredder and separating the shredded leaf fragments from the shredded butts and delivering the shredded leaf fragments to tobacco stripped from the leaves by said mechanism, and said winnowing fan including a rotating winnowing fan travelling in unison with one of said shredding members to remove the shredded tobacco from between said shredding members and winnow it into stem fragments and leaf fragments.
50. 20. The combination with a butt thresher, of mechanism for stripping tobacco from the stems of tobacco leaves, means for forwarding tobacco leaves into the range of action of said thresher and stripping mechanism successively, a shredder arranged to receive leaf fragments and broken butts from said thresher and shred the same and thus remove any leaf fragments adhering to the broken butts, the said shredder being in such proximate relation to the thresher that no substantial change in the condition of the leaf fragments and butts can occur during the transfer of the same from the thresher to the shredder, means for delivering said butts and fragments from said thresher to said shredder and a winnowing fan for removing the shredded tobacco from said shredder and separating the shredded leaf fragments from the shredded butts.

RUPERT E. RUNDELL.
